UNITED STATES PATENT OFFICE.

EDWARD L. DAILEY, OF EVANSVILLE, MINNESOTA.

TYPEWRITER ATTACHMENT.

Application filed September 16, 1922. Serial No. 588,674.

To all whom it may concern:

Be it known that I, EDWARD L. DAILEY, a citizen of the United States, residing at Evansville, in the county of Douglas and State of Minnesota, have invented new and useful Improvements in Typewriter Attachments; of which the following is a specification.

This invention relates to an attachment for typewriters, the general object of the invention being to provide means for folding the paper as it leaves the platen of the typewriter so that it may be easily placed in an envelope.

Another object of the invention is to so arrange the parts that the paper can be placed in an envelope by the device.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a view of a typewriter showing my invention in use.

Figure 2 is an enlarged plan view of the device itself.

Figure 3 is a section on line 3—3 of Figure 2.

Figure 4 is a section on line 4—4 of Figure 2.

Figures 5, 6 and 7 are detail views.

In these views 1 indicates a pair of supporting arms which are adapted to be connected with a part of the carriage of a typewriter as shown in Figure 1. A rod 4 is rotatably mounted in said arms 1, said rod being provided with a loop 4' and a crank 4''. The cranked end extends to a casing 5 carried by one of the arms 1 where the crank engages an adjustable stop 5' carried by the casing which limits the rotary movement of said rod in one direction. A plate 2 is hinged to the rod 4, as shown at 3, and the upper edge of said plate is curved, as shown at 6, to act as a stop for the paper sheet. Spring arms 7 are provided for holding the paper to the plate, these arms being provided with curved ends 8 for guiding the paper as it comes from the platen to the upper face of

the plate. A yoke 9 has its ends provided with eyes 9' which engage sleeves 10 on the rod 4. The bight of the yoke is offset. One of the sleeves 10 extends into the casing 5 where it engages an eye 11' of a crank shaft 11 which has one end extending through the casing, said extended end receiving a button 11'' so that the shaft can be manually operated. A spring 12 in the casing engages the crank of the shaft and tends to hold the same in lowered position. The stop 5' acts to hold the rod 4 in such a position that the loop 4' will hold the plate 2 so that the paper coming from the platen will pass over the same and under the arms 7. By adjusting the stop 5' the plate can be placed in proper position relative to the platen to receive the paper therefrom. Spring 12 acting on shaft 11 will cause the same, through the sleeve 10, to hold the yoke 9 in raised position so that the paper can pass between the yoke and plate. When the upper edge of the sheet strikes the curved part 6 further movement of the upper part of the sheet will be prevented and the sheet will have a tendency to fold at the lower edge of the plate and then pass up the rear side of the plate. If the sheet does not fold it can be made to do so by rotating the shaft 11, by means of the button 11'', in an anti-clockwise direction thus revolving the sleeve 10 and forcing the yoke 9 downwardly against the sheet and thus folding it over the lower edge of the plate. When a new sheet of paper is to be placed in the machine the shaft is turned in a clockwise direction so as to cause the crank to strike the crank 4'' of the rod 4 so that the loop 4' will engage the plate and tilt the same upwardly so as to take the same and the yoke away from the platen to permit a new sheet to be placed in the machine.

I may also provide a pair of spring arms 7' at the rear of the plate to hold the part of the sheet which is folded over the rear face of the plate and I also provide a spring latch 12 in the case for engaging the crank shaft 11 for holding the parts in inoperative position.

This device will fold the paper so that it can be placed in an envelope and if desired an envelope can be passed through the machine so that the name and address can be printed thereon and by raising the flap before placing the envelope in the machine the envelope will receive the plate and the folded sheet thereon as the envelope passes

from the machine so that it is only necessary to swing the plate upwardly and remove the envelope with the sheet therein from the plate.

5. If desired a combined envelope and letter sheet may be used with the device, the device folding the letter sheet and then placing it in the envelope part as the sheet leaves the machine.

10. It is thought from the foregoing description that the advantages and novel features of my invention will be readily apparent.

15. I desire it to be understood that I may make changes in the construction and in the combination and arrangement of the several parts, provided that such changes fall within the scope of the appended claims.

What I claim is:—

20. 1. A device of the class described comprising a rock shaft, means for supporting the same on a carriage of a typewriter, a plate hinged to the shaft, a yoke carried by the shaft, means for normally holding the 25 yoke above the plate, means for forcing the

yoke downwardly to fold a sheet of paper over the lower edge of the plate and means for moving both the plate and yoke upwardly.

2. A device of the class described comprising a pair of supporting arms attached to the carriage of a typewriter, a crank shaft rotatably mounted in the same, a loop on the shaft, a casing connected with one of the supporting arms and in which the cranked end of the shaft is located, a plate hinged to the shaft, a pair of spring arms associated with the plate, said plate resting against the loop, sleeves on the shaft, a yoke having its ends connected with the sleeves, a short crank shaft carried by the casing and having one end projecting therefrom and its other end connected with the sleeve, a handle on the projecting end, a spring engaging the short crank shaft for holding the yoke in raised position and an adjustable stop engaging the cranked end of the main crank shaft.

In testimony whereof I affix my signature.
EDWARD L. DAILEY.
